DESIGN FOR A PENCIL POUCH

Henry Hassenfeld, Providence, R. I.

Application December 9, 1935, Serial No. 59,965

Term of patent 3½ years

To all whom it may concern:

Be it known that I, Henry Hassenfeld, a citizen of the United States, residing at Providence, in the county of Providence and State of Rhode Island, have invented a new, original, and ornamental Design for a Pencil Pouch, of which the following is a specification, reference being had to the accompanying drawing, forming a part thereof.

Fig. 1 is a front elevational view of a pencil pouch showing my new design.

Fig. 2 is a rear elevational view of the same.

Fig. 3 is a perspective view of the same, showing the pencil pouch in open condition.

I claim:

The ornamental design for a pencil pouch, as shown.

In testimony whereof I have affixed my signature.

HENRY HASSENFELD.
